UNITED STATES PATENT OFFICE

THOMAS S. DERR, OF BROOKLINE, MASSACHUSETTS, ASSIGNOR TO THE BRISTOL COMPANY, OF WATERBURY, CONNECTICUT, A CORPORATION OF CONNECTICUT

VENTING DEVICE FOR LIQUID AND VAPOR APPARATUS

Application filed March 2, 1925. Serial No. 12,802.

The invention relates to means for venting non-condensable gases, especially from liquid containers, for example, water level apparatus such as may be utilized in connection with the determination or automatic maintenance of the water level of a steam boiler. Apparatus for such maintenance and determination is set forth in U. S. Patent No. 1,357,850, granted to me on the 2nd day 10 of November, 1920, and wherein thermoelectric couples are disclosed as one means for effecting the desired result, although it is to be understood that the present invention is not to be restricted to the use of such measuring or control devices, and any suitable means responding to a difference in temperature existing, for example, between a water column and a contiguous column of steam may be employed.

20 In connection with the particular embodiment aforesaid, it will be appreciated that the same will afford accurate and reliable indications so long only as the column of steam is maintained contiguous to the varying column of water. In other words, should the steam column be replaced by or become mixed with non-condensable gases, as may result from the condensation of steam in the system, the temperature relationship between steam 25 and water would be disturbed and the measuring system or control would no longer function correctly.

It is the object of the present invention to provide novel venting means whereby to prevent such replacement or mixture from occurring and particularly thru the provision of means whereby any non-condensable gases accumulating in the system will first be conducted to a point more or less remote from 30 the region of measurement and then vented from the system either manually or automatically.

The nature of the invention, however, will best be understood when described in connection with the accompanying drawings, in which—

50 Fig. 1 is an elevation showing the general arrangement of apparatus, with a portion of the protective casing and supplementary water column being broken away.

Fig. 2 is a detail elevation of an automatic venting valve, with portion of the casing broken away to disclose the interior.

Fig. 3 is a detail vertical section of the valve mechanism and outlet.

Referring to the drawings, 10 designates a suitable container for a liquid, for example, in connection with the particular embodiment herein set forth, a supplementary gauge or water level column which is intended to be connected at the top and bottom in the usual manner, as thru suitable pipes 11 and 12, with a boiler (not shown). This column may be surrounded by a suitable protective casing 13, if desired. Similarly to the arrangement disclosed in the aforesaid patent, the container 10 for the water column is designed to have associated therewith a temperature responsive device 14 which may be connected to various measuring instruments 60 as the indicating and recording devices 15. The arrangement thus far described is similar to that set forth in my said prior patent; but it has been found that in the use thereof unless the container 10 be periodically blown 65 off, as thru a blow-off valve 16, the indications of the measuring apparatus will become erratic due to the accumulation of non-condensable gases at one or more points along the column and which gases are naturally at a 70 different temperature from that of the steam constituting one of the measuring media. However, a blow-off valve is manually controlled and its periodical operation therefore not dependable. It has also been found 75 that the provision of ordinary automatic air venting means in direct connection with the column would not operate satisfactorily in practice, especially with temperatures obtaining at steam pressures as high as 250 lbs. 80 per square inch.

It has been found necessary, therefore, to provide means for first conducting the non-condensable gases away from the column itself before effecting the venting thereof. In 85 accordance with the present invention, this is accomplished by providing a vent pipe 20 which communicates with the container or column, as by extending along the length of the said water column to near the bottom 100

thereof and then outwardly beyond same and thru the connecting T 21 for the boiler connection 11, and to the top of which T is connected suitable means for venting the gas. 5 This venting means may consist of any suitable or specially designed valve 22 for permitting the automatic or manual release of gases from within the valve body. Moreover, in order to insure the collection and delivery 10 of the gases to said valve body, at varying liquid levels as in accommodating fluctuations in level of the water, the pipe 20 is perforated at various points along its length, as shown, to pick up the gases as they may accumulate 15 along said column. Furthermore, it is preferable to construct the valve 22 with proportionately large radiating surface, as it has been found desirable to cause condensation of any steam occupying space therein, the 20 water of condensation trickling back thru the tube 20 and absorbing small amounts of non-condensable gases in its passage downwardly.

An especially suitable type of valve is 25 shown in Figs. 2 and 3 of the drawings, the ordinary type being unsatisfactory in view, among other reasons, of the comparatively high temperatures and pressures employed. No claim, however, is made herein to this 30 specific type of valve. As shown, the valve consists of a body 25 which is connected at one end to the tube 20 thru an elbow 26 and a connecting pipe 27 of required length. The valve body is of the T type and receives 35 in its top opening an extension piece 28 closed by a plug 29. The latter has soldered or otherwise secured thereto a thermostatic element as a bi-metallic actuating strip or moving element 30 which, as is well understood, will be affected by differences of temperature to provide a slight movement substantially at right angles to its length. At its outer and free end, this strip is adjustably secured to a valve stem 31 as by being mounted between suitable nuts 30' and 30" working thereon; said stem being mounted substantially co-axially with the horizontal axis of the valve 32. The latter is designed to fit in a valve seat or cavity 33 provided in a plug 34 closing the end of the valve body opposite its elbow connection end. The plug, however, is bored axially thru; the opening passing also thru the valve seat 33; and the said stem is provided with an extension 40 35 beyond the ball valve portion; which extension fits thru the bore of the plug with a slight clearance provided therebetween. Movement of the valve stem, due to the influence of temperature variations upon the 45 strip, will thus cause the ball to seat or unseat itself in the valve seat 33 to seal or open respectively the outlet thru the plug 34. At the same time, the reciprocatory movement of the extension 35 will serve to keep this 50 55 opening clear at all times—insuring the vent-

ing of the gases from the valve, and which will occur until steam reaches the bi-metallic strip to cause thereby the same to close the valve at its seat 33. In the provision of the extension piece 35, furthermore, a ready means is afforded for indicating by the amount projecting whether the valve is sealed or open; and external control is afforded thereby, as by pressing inwardly thereon so that the valve may at any time be caused to 75 open.

In the foregoing apparatus, any gases tending to collect or collecting in the container 10 will be picked up thru the perforations of the tube 20 and conducted thru the latter to the valve 22 from which the same are released until the steam again closes this valve. Thereby, the column is suitably vented and thus maintained at all times in proper condition for effecting measurement 85 or control thru the variation in level of liquid therein, when this is contemplated.

It will be appreciated, for example, in water columns attached to steam boilers and similar apparatus where a liquid is in contact 90 with its vapor, that the water column is continually condensing the steam inside it because of loss of heat to the surrounding air. There is consequently a slow current of steam entering the water column all the time. If 95 this steam contains minute amounts of other gases, such as nitrogen or air, the steam will be condensed and these gases will be left behind until after a period of time the water column will contain a mixture of steam and 100 non-condensable gases and the non-condensable gases may be a very large proportion of the mixture. To a certain extent these non-condensable gases will be carried away by solution in the water formed by condensation of the steam and in this manner will be carried out of the bottom of the column 105 back into the boiler again. In many cases, however, and especially with low pressure or poor feed water or irregular feeding of water 110 to the boiler, it has been found that the rate of accumulation of the gases is very much greater than the rate at which they can be carried out; and in many instances it has been observed that these gases constituted 115 such a large proportion of the steam-gas mixture as to make the water column almost cold to the touch for an appreciable distance above the water level. The said gases will be carried to the region directly over the 120 water, and it is necessary, therefore, to have some device which will skim them, as it were, from just above the water. This invention sets forth just such a device.

By means of a vertically disposed tube 125 with several holes in it the gases are drawn up through the tube into a venting device which permits them to escape to the surrounding atmosphere. The perforated tube running down the interior of the apparatus 130

has some holes above the normal water level and some below it, but the spacing of the holes is such that at the highest water level ordinarily reached one hole at least will be above the water and the lowest level ordinarily reached will be but a short distance below the lowest hole. With intermediate water levels some holes will be submerged and inoperative.

The venting device is shown in the drawings as an automatic venting valve; and if the steam in the interior of it is continually condensing because of loss of heat to the surrounding atmosphere, the water formed by condensation trickles down the interior of the perforated tube which leads to the said venting device. Fresh steam then rises in the tube to take the place of the steam condensed. It will be noticed, by reference to the drawings, that this steam is drawn in part, at least, from the region directly over the liquid and so if there is air or non-condensable gases mixed with the steam directly over the liquid, this air will be drawn up into the venting device and since it cannot condense and run back into the apparatus again, the air or non-condensable gases will accumulate in the venting device from which they can be discharged.

In this particular embodiment, a thermostatic valve is shown, which will open and permit the non-condensable gases to escape when they have accumulated in sufficient amounts to make the temperature of the valve materially less than the temperature it would have if filled entirely with steam. Should the valve seat leak slightly, the operation would be continuous instead of intermittent and the non-condensable gases would escape together with a small quantity of steam.

It will be observed that a venting device of the character set forth herein can be used in connection with any liquid in contact with its vapor where the vapor contains noncondensable gases and where it is desired to separate the vapor from the non-condensable gases.

I claim:

1. The combination with apparatus responsive to a difference in temperature, a container for liquid of varying level associated with said responsive apparatus having elements both in the liquid and above its normal level, and connections to the container above and below the level of the liquid therein for a condensable gaseous medium; of venting means for eliminating from said container non-condensable gases, and comprising a tube inserted therein and having openings along its length affording communication at all times with the space above said liquid, and a venting member connected with said tube for releasing non-condensable gases therefrom.

2. The combination with apparatus responsive to a difference in temperature, and a container for liquid of varying level, said container being adapted for connection with a steam boiler and associated with said responsive apparatus, the latter having elements both in the liquid and above its normal level; of venting means for eliminating from said container non-condensable gases, and comprising a tube extending therein and outwardly therefrom, said tube having openings along its length affording communication at all times with the space above said liquid, and an automatic thermostatically-operated venting member connected with the outer end of said tube opening to release non-condensable gases and closing upon delivery of steam to said venting means.

3. The combination with apparatus responsive to a difference in temperature, and a container for liquid of varying level, said container being adapted for connection with a steam boiler and associated with said responsive apparatus, the latter having elements both in the liquid and above its normal level; of venting means for eliminating from said container non-condensable gases, and comprising a tube extending therein and outwardly therefrom, said tube having openings along its length affording communication at all times with the space above said liquid, and a thermostatically controlled valve connected with the outer end of said tube and opening to release non-condensable gases and closing upon delivery of steam to said venting means.

4. The combination with apparatus responsive to a difference in temperature, and a container for liquid of varying level, said container being adapted for connection with a steam boiler and associated with said responsive apparatus, the latter having elements both in the liquid and above its normal level; of venting means for eliminating from said container non-condensable gases, and comprising a tube extending therein and outwardly therefrom, said tube having openings along its length affording communication at all times with the space above said liquid, and an automatic thermostatically-operated venting member with proportionately large radiating surface connected with the outer end of said tube and opening to release non-condensable gases and closing upon delivery of steam to said venting means.

5. The combination with a container for liquid of varying level, a fitting at the bottom thereof and a T at the top for connection to a boiler, and means responsive to a difference in temperature located within the container and having elements both in the liquid and above its normal level; of a tube extending through the T into said container and having openings along its length affording communication at all times with the

space above said liquid, and a venting valve in communication with the outer end of said tube.

6. In combination: a container for liquid of varying level, a tube mounted therein having openings along its length affording communication at all times with the space above said liquid, and thermostatically controlled means connected with said tube for automatically venting non-condensable gases therefrom.

Signed at New York, in the county of New York and State of New York this 13th day of February, A. D. 1925.
